Primary Examiner — Jonathan J Han(74) Attorney, Agent, or Firm — Banner & Witcoff, Ltd.CLAIM

The ornamental design for a shoe, as shown and described.

DESCRIPTION

FIG. 1 is a front perspective view of a shoe showing my new design;

FIG. 2 is a side view thereof; and,

FIG. 3 is a rear perspective view thereof.

The two broken line circles within the photographic area represent eyelets and form no part of the claimed design. The broken lines depicting the remainder of the shoe form no part of the claimed design.
